UNITED STATES PATENT OFFICE.

WESLEY PANGRAC, OF NILES, KANSAS.

WEDGE-CUTTER.

SPECIFICATION forming part of Letters Patent No. 695,336, dated March 11, 1902.

Application filed October 26, 1901. Serial No. 80,072. (No model.)

To all whom it may concern:

Be it known that I, WESLEY PANGRAC, a citizen of the United States, residing at and whose post-office address is Niles, in the county of Ottawa and State of Kansas, have invented new and useful Improvements in Wedge-Cutters, of which the following is a specification.

My invention relates to wedge-cutters; and its object is to provide a simple, inexpensive, and effective hand-operated machine for cutting wooden wedges.

The invention comprises a frame or standard adapted to be clamped in a vise and provided with a seat and cutting-block and a lever having a knife-edge and pivotally secured to the frame.

The construction of the improvement will be fully described hereinafter in connection with the accompanying drawings, which form a part of this specification, and its novel features will be defined in the appended claims.

In the drawings, Figure 1 is a view in perspective of a wedge-cutter embodying the invention. Fig. 2 is a vertical section thereof on the line 2 2 of Fig. 1, and Fig. 3 is a section on the line 3 3 of Fig. 1.

The reference-numeral 1 designates a frame or standard formed at its upper end with a lateral extension 2 and on one side of its upper end with a wedge-shaped recess 3. A plate 4 is secured to the bottom wall of the recess by a bolt 5 and nut 5^a.

6 designates a cutting-block, preferably of wood, supported between horizontal shoulders 7 and 8 of the standard and secured by a bolt 9 and a nut 10.

The lever 11 is formed with a depending lug 12 and is fulcrumed upon a shouldered bolt 13, which extends through an oblong opening 14, formed in the standard. A sleeve 15 is arranged within this opening, and bearing against the inner end thereof is a washer 17, mounted on the threaded end of the bolt 13. A nut 16 is also arranged upon said end of the bolt and is adapted when screwed inward to clamp the washer against the sleeve and hold the bolt 13 against movement within said sleeve. When the cutting edge 18 of

the lever 11 wears away to such an extent 50 that it will not contact with the cutting-block 6 along the entire upper edge thereof, it is merely necessary to loosen the nut 16, so that the bolt 13 can be slid downward within the sleeve 15 until said cutting edge assumes its 55 proper position in relation to the block 6. The washer 17 is then again clamped against the sleeve 15, thereby locking the said bolt in its adjusted position. This adjustment of the bolt can be repeated as the cutting edge 60 18 wears off. The under portion 18 of the lever 11, adjacent to its fulcrum-point, is reduced to a cutting edge, while its free end 19 serves as a handle.

I preferably form an opening 20 near the 65 lower end of the standard to adapt the device to be hung up when not in use.

The operation of the improvement will be readily understood. A block of wood sawed to the required size is placed within the seat 70 3 and rests upon the block 6. The lever is then forced down to split the block, and thus form the wedge.

It will be understood that the inclination of the plate 4 may be readily varied by inserting a spacing or filling strip of pasteboard or other material behind it.

I claim—

1. The combination with a standard having a recess in one face thereof and a wedge-shaped recess at its upper end; of a lateral extension thereto, a wear-plate secured within the wedge-shaped recess, a cutting-block detachably secured within the face-recess of the standard, the upper edge thereof being in 85 alinement with the lower edge of the wedge-shaped recess, a lever pivotally secured to the extension of the standard and having a cutting edge thereto and a vertically-adjustable pivoted bolt to said lever. 90

2. The combination with a standard having a recess in one face thereof and a wedge-shaped recess at its upper end; of a lateral extension to said standard, an adjustable wear-plate secured within the wedge-shaped 95 recess, a cutting-block detachably secured within the face-recess, the upper edge of said block being in alinement with the lower edge

of the wedge-shaped recess, a lever pivoted to the extension and having a cutting edge adapted to bear upon the cutting-block, a pivoted bolt to said lever projecting through the extension and movable vertically therein and means upon the bolt for clamping the same in adjusted position.

In testimony whereof I affix my signature in presence of two witnesses.

WESLEY PANGRAC.
